GOLF PUTTER HEAD

Jack R. Calton, 1115 Brooklyn Ave.,
Salt Lake City, Utah 84104

Filed Dec. 5, 1973, Ser. No. 421,757

Term of patent 14 years

Int. Cl. D21—02

U.S. Cl. D34—5 GH

FIG. 1 is a perspective view of a golf putter head showing my new design;

FIG. 2 is a perspective view, showing the putter face;

FIG. 3 is a rear elevation, showing the hollow aperture extending laterally into the interior of the putter head;

FIG. 4 is a front elevation, showing the putter face;

FIG. 5 is a top plan view of the putter;

FIG. 6 is a right side elevation, showing the heel of the putter; and

FIG. 7 is a left side elevation, illustrating the toe of the putter, in this instance a right-handed putter.

I claim:
The ornamental design for a golf putter head, substantially as shown.
